UNITED STATES PATENT OFFICE.

OTTO MAKI AND KARL ARLIN, OF PALMER, MASSACHUSETTS.

SWITCH-OPERATOR.

1,392,188.

Specification of Letters Patent. Patented Sept. 27, 1921.

Application filed April 7, 1921. Serial No. 459,460.

To all whom it may concern:

Be it known that we, OTTO MAKI and KARL ARLIN, citizens of the Republic of Finland, residing at Palmer, in the county 5 of Hampden and State of Massachusetts, have invented certain new and useful Improvements in Switch-Operators, of which the following is a specification.

This invention relates to switch operating 10 mechanisms and more particularly to that form of operators carried below the front platform of a car for instance, and adapted to be operated by the foot of the motorman to open or close a switch.

15 The primary object of the invention resides in the construction of a novel and improved switch operator adapted to be carried below the front car platform to be actuated by a foot pedal whereby a switch 20 operating extension may be actuated to the left or right to open and close a switch to permit the car to travel in its proper direction.

Another and very important object of the 25 invention resides in the provision of a spring controlled foot operated device capable of being installed on various types of railway rolling stock and which is preferably provided with a foot pedal to selectively de- 30 press the right or left hand switch operator whereby the enlarged extension carried by the switch may be thrown to the left or right as desired and thus direct the travel of the car thereby.

35 A continued and further object of the invention resides in the novel and improved construction of a switch operator which is extremely simple, consisting of comparatively few parts therefor inexpensive to 40 manufacture, highly efficient and positive in operation, strong and durable, wherein the parts are so arranged as not to get out of order, and otherwise capable of being manufactured at an extremely low cost where- 45 by its commercial possibilities are greatly enhanced.

With these objects in view and others which will be manifest and suggested as the purpose and nature of our invention are 50 revealed in the following specification and drawing wherein we have shown a preferred embodiment thereof,

Figure 1 is a side view showing the operator as mounted beneath the front platform 55 of a car.

Fig. 2 is a perspective view showing the

foot pedals and switch operating shoes supported beneath the platform and between the tracks for engaging the switch extension.

Fig. 3 is a diagrammatic view showing 60 the invention as applied to one type of switch.

Fig. 4 is a similar diagrammatic view showing the invention as applied for another 65 type of switch.

Referring now to the drawings wherein like parts designate corresponding parts throughout the specification, numeral 5 designates the front portion of a railway 70 car which may be of conventional design having a front platform 6 beneath which we have provided an inclosed, substantially rectangular casing 7 for confining the switch operating mechanism now to be described 75 in detail.

The switch operating mechanism primarily comprises a pair of substantially L-shaped, flat metallic levers, 8, 9, preferably pivotally connected as at 10 within and in 80 the forward portion of the casing 7, said 85 levers being held in their normally raised, inoperative position by flat, leaf springs 11 which are secured as at 12 to the flooring 13 of the casing as clearly shown by Fig. 1 of the drawing.

Each of the levers 8, 9, are provided with a vertical spindle 14 extending through a slot or recess 15 in the floor 6 and carry flat, knurled foot pedals 16 whereby the respective levers 8, 9, may be depressed to actuate 90 the switch extension subsequently to be referred to. The vertical arm 17 of each lever above referred to is adapted to move freely 95 through a slot or recess 18^a formed in the bottom 13 and near the rear thereof, said arm 17 supporting the flat, horizontal shoes 18 each of which are provided with an inwardly 100 curved cam plate 19 for engaging the diamond shaped extension 20 on the end of the pivotally connecting arm 21.

Referring now to Fig. 3, it will be noted that the arm 21 which is pivoted as at 22 operates the lever 23 and link 24 whereby the switch 25 may be actuated to the left or right and thus direct the travel of the machine in the desired direction. Of course, the switch operating mechanism is arranged below the front platform and between the main track 26 so that the same will positively engage the diamond shaped extension 110 20 to operate the switch.

In the form of the invention shown by

Fig. 4, wherein the switch 27 is arranged for operation to control the direction of travel to the left or right, the same principle and operation is involved as above described, the 5 switch 27 as well as the switch 25 operating in suitable fish plates (not shown) when the same is actuated by the movement of the right or left hand levers 8, 9, when the respective shoe 18, shown in dotted lines, engages the diamond shaped extension 20 to the left or right as shown. In other words, the operation of the switch may be controlled from a position on the front platform of a car by depressing the right or left 10 hand lever, and when the operator removes his foot from the pedal, the said levers will return to their normal, inoperative position as will be apparent.

In the accompanying drawings, we have 20 illustrated our invention embodied in one form by way of example, and which in practice has been found to be highly satisfactory in obtaining the desired results. It will be obvious however that other embodiments 25 may be adopted and that various changes in the details of construction may be resorted to by those skilled in the art without departing from the spirit and scope of the invention. It is furthermore understood that the 30 invention is not necessarily limited or restricted to the precise elements shown except in so far as such limitations are specified in the subject matter being claimed.

Having shown and described our invention, what we now claim as new and desire to secure by Letters Patent of the U. S. is:—

1. A switch operating mechanism comprising a pair of bent levers adapted to be pivotally connected beneath the front 40 platform of a car, each of said levers having a

vertical arm extending below the platform and supporting a switch point operating shoe at its terminal, a foot pedal for depressing said shoe to its operative position and resilient means for maintaining said 45 shoes in their raised, normally inoperative position.

2. A switch operating mechanism comprising a pair of bent levers adapted to be pivotally connected within a casing beneath 50 the front platform of a car, each of said levers having a vertical arm extending below the casing and supporting a switch point operating shoe at its terminal, said shoe being provided with a cam surface for 55 engaging a switch arm extension, a foot pedal for depressing each of said levers and resilient springs for maintaining said levers and shoes in their raised, normally inoperative position.

3. A switch operating mechanism comprising a pair of substantially L-shaped levers pivotally connected at one end within a casing beneath the front platform of a car, each of said levers having a vertical arm 60 extending through and below the casing and supporting a horizontal switch point operating shoe at its lower terminal position between the tracks, said shoes being provided with inner cam surfaces for engaging an enlarged, switch arm extension 65 between the tracks, a foot pedal for depressing each of said levers, and resilient means engaging the L-shaped levers for maintaining the shoes in their raised, nor- 70 mally inoperative position.

In testimony whereof we affix our signatures hereto.

OTTO MAKI.
KARL ARLIN.
